UNITED STATES PATENT OFFICE.

FREDERICK W. BACORN, OF SEWICKLEY, PENNSYLVANIA.

SHAVING-BRUSH.

1,178,833.

Specification of Letters Patent. Patented Apr. 11, 1916.

Application filed July 1, 1915. Serial No. 37,619.

To all whom it may concern:

Be it known that I, FREDERICK W. BACORN, a citizen of the United States, residing at Edgeworth, Sewickley, in the county of Allegheny and State of Pennsylvania, have invented certain new and useful Improvements in Shaving-Brushes, of which the following is a specification.

This invention relates to certain new and useful improvements in shaving brushes and it has for its objects among others to provide a simple, novel form of shaving brush applicable for use with a tube of shaving cream, a stick of shaving soap, or shaving powder or analogous preparations.

It has for a further object to provide a brush which will serve to work up a good lather and to rub the same into the face, and at the same time effectually hold the lather and prevent the same from running down the handle and onto the hand of the user.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a view partly in elevation and partly in substantially central longitudinal section, showing a brush embodying my present improvement. Fig. 2 is an end view thereof. Fig. 3 is a detail showing a portion of the slotted elastic band.

Like numerals of reference indicate like parts throughout the different views.

In carrying out my invention I take a disk of rubber sponge or the like 1, the outer face of which is preferably slightly concave, as at 21, the other face being cemented or otherwise affixed to a suitable base or support 3 which may be in the form of a handle, as shown, or otherwise, as may be found most expedient. Next I take a strip of elastic or resilient material, preferably a strip of thin bandage gum, as seen at 4, and by any suitable means slit the outer edge thereof, as seen at 5, the slits being any required distance apart and of proper depth, say practically one thirty-second of an inch apart and one-half an inch, more or less, in depth. This I wind

around the disk of rubber sponge 1, the lower edge thereof being extended a sufficient distance below the inner edge of the disk and, in the present instance shown as engaging a shoulder 6 of an annular recess 7, to give a sufficiently firm support. This strip I wind a plurality of times, three being generally found sufficient, and preferably I so wind the strip that the first row of fringe is somewhat below the second row 65 8 and the second a little lower than the third row 9. This forms a receptacle and works up a good lather and rubs it in. The rubber strip employed is comparatively thin, being say only about one sixty-fourth 70 of an inch thick, and the shoulder or annular recess would be comparatively shallow, say about three sixty-fourths of an inch deep. In Fig. 1, these proportions are somewhat exaggerated for the sake of better illustrating the structure. It will thus be seen that I have a fringe consisting of a plurality of annular bands, which may or may not be integral one with the other and the outer edge of each successive band 80 extending slightly beyond the others, as shown in Fig. 1.

The rubber sponge carries water, assists in working up the lather, and affords a surface sufficiently firm to permit of the 85 lather being rubbed in and the beard thereby better softened. Other material, such as natural sponge, may be substituted for the rubber sponge.

The annular bands have a tendency to 90 keep the lather from working off the surface of the sponge and onto the handle; and when slotted in the manner shown, the fringe produced simulates the action of a brush, working up the lather, softening the 95 beard, and spreading the lather evenly over the face. It is obvious that a brush-like fringe may be produced otherwise than as herein described, or even by the use of material other than rubber. By slitting the 100 outer edges of the annular bands I find that greater resiliency is obtained without danger of breakage of the fringe in use and a better holder for the lather is provided.

In some cases I may employ an ornamental band, as shown at 10, surrounding and affixed to the outer annular edge or portion of the base 3 and of sufficient width to embrace the annular bands of rubber, as seen in Fig. 1. This may be of nickel or any 110

other suitable material and is employed not only for ornamentation, but as additional means of holding the rubber bands in place, which latter may be cemented to each other, if desired. This ornamental band also covers up and conceals the recess and the inner ends of the elastic bands.

The rubber bands may, in some instances, be arranged so as to compress the outer portions of the rubber sponge disk while the inner portions, that is the portions toward the center, are practically open.

Modifications in details may be resorted to without departing from the spirit of the invention or sacrificing any of its advantages.

What is claimed as new is:—

1. A shaving brush embodying a disk of rubber sponge, a base therefor, and an elastic band embracing the disk and having its edge extended outward beyond the same.
2. A shaving brush embodying a disk of rubber sponge, a base therefor, and an elastic band embracing the disk and having its edge extended outward beyond the same and slit.
3. A shaving brush embodying a disk of rubber sponge, a base therefor, and an elastic band embracing the disk and having its edge extended outward beyond the same, said band being composed of a plurality of concentric pieces of elastic material.
4. A shaving brush embodying a disk of rubber sponge, a base therefor, and an elastic band embracing the disk and having its edge extended outward beyond the same, said band being composed of a plurality of concentric pieces of elastic material, the

outer edges of the pieces extended one beyond the other.

5. A shaving brush embodying a disk of rubber sponge, a base therefor, and an elastic band embracing the disk and having its edge extended outward beyond the same, said band being composed of a plurality of concentric pieces of elastic material, the outer edges of the pieces extended one beyond the other and slit.

6. A shaving brush comprising a base, a disk of rubber sponge secured thereto and having its outer face concave, and a fringe surrounding said disk and secured to the base, said fringe comprising a plurality of annular wrappings of elastic material, each successive wrapping extending beyond the others.

7. A shaving brush comprising a base, a disk of rubber sponge secured thereto and having its outer face concave, and a fringe surrounding said disk and secured to the base, said fringe comprising a plurality of annular wrappings of elastic material, each successive wrapping extending beyond the others and having their outer edges longitudinally slit.

8. A shaving brush comprising a base, a disk of absorbent material, and a brush-like fringe of elastic material surrounding said disk and extending beyond the face thereof.

9. A shaving brush comprising a disk of absorbent material, a base therefor, and a surrounding member in the form of elastic bands, said disk and member coöperating to produce a combined rubbing-in and brush-like effect.

FREDERICK W. BACORN.
